UNITED STATES PATENT OFFICE

WALTER S. BRADEBURY AND AUBREY L. LOWE, OF ILION, NEW YORK, ASSIGNEES TO
REMINGTON ARMS COMPANY, INC., A CORPORATION OF DELAWARE

FIREARM

Application filed March 23, 1931. Serial No. 524,534.

This invention relates to firearms and has been illustrated as applied to a firearm embodying an action of the so-called "Martini type", one example of which is illustrated in the patent to Martini, No. 90,614, May 25, 1869.

One object of the invention is to provide an improved breech locking device particularly adapted for use in a breech mechanism 10 of the general type disclosed in said Martini patent.

A further object of the invention is to provide an efficient ejector mechanism particularly adapted to a firearm of the Martini 15 type.

In the drawing:

Fig. 1 is a sectional elevation on substantially a central line through the barrel and forearm and through the receiver upon a line 20 adjacent one receiver wall.

Fig. 2 is a plan view of the receiver.

Fig. 3 is a fragmentary side elevation of the inside of a receiver wall.

Fig. 4 is a perspective view of the improved ejector detached from the firearm.

The firearm comprises a barrel assembly which includes a barrel 10 and fore-end 11, secured in a breech piece 12. Said barrel assembly is attached to a receiver, indicated 30 generally by the numeral 13, by means of a take-down screw 14 which, in the present construction, extends upwardly through an aperture in the bottom of the receiver and is threaded into the breech piece 12, in the manner illustrated in Fig. 1.

Pivoted on a stud 15, which extends transversely of the receiver, is a breech block 16, the top of which is exposed through the open top of the receiver. The breech is opened by 40 swinging the forward end of said breech block downwardly about the stud 15 in the manner to be presently described. According to the present invention, the breech block is provided near its forward end with lateral 45 lugs or ribs 17 adapted, in the closing movement of the breech block, to engage in suitable grooves 18 in the sides of the receiver. The recoil of the breech block is thus taken up by the margins of said slots and, to insure 50 engagement of the lugs 17 therewith pre-

venting the recoil from being transmitted to the stud 15, the opening in the breech block which receives the stud 15 is slightly elongated transversely, as indicated in Fig. 1.

The breech block is swung about the pivot 55 15 to open and close the breech by the manipulation of a finger piece 19 pivoted in the receiver at 20 and provided with upstanding arms 21 which engage suitable cam slots in the sides of the breech block. Said breech 60 block contains a firing pin or striker 22 controlled by a sear 23 having a forwardly projecting part 24 adapted for engagement with the trigger 25. Said striker is cocked by the movement of finger piece 19 necessary to open 65 the breech through the engagement of an upwardly facing shoulder 211 on said finger piece with the underside of the part 24 of the sear.

Pivoted at 26 in the breech piece is an extractor 27 the upper end of which lies in a suitable recess in said breech piece and barrel 10 and is suitably notched and rabbeted to receive the lower part of the rim of a cartridge in the chamber and to form a continuation 70 of the breech face of the barrel. Said extractor is provided with a rearwardly extending projection 28 adapted to be engaged by the breech block in its downward or breech opening movement, thereby loosening or extracting the cartridge or cartridge shell in 75 the chamber.

The present invention contemplates the provision of an ejector device which may be constructed as follows: In a suitable recess 80 in the fore-end 11 is inserted a housing 29 adapted to contain an ejector spring 30 and a spring follower 21. The spring follower projects from said housing and is formed integral with or suitably connected to an ejector 85 32 which passes through an aperture in the breech piece 12 and terminates immediately in front of the extractor 27. The connection from the spring follower 31 to the ejector 32 90 may comprise a follower head 33 and guide 95 member 34 cut out to conform to the curvature of the barrel 10 to accurately guide the movement of the ejector. It will be apparent that if the cartridge in the chamber has been fired, the fired shell will be expanded into 100

sufficiently tight contact with the chamber walls to remain unmoved until the breech block engages the extractor tail 28; notwithstanding the extractor is, during downward movement of the breech block, subjected to the pressure of ejector spring 30. When the breech block engages the tail 28 the cartridge will be loosened and thereupon the extractor is snapped rearwardly by the ejector spring, thereby positively and forcibly ejecting the fired shell.

The movement given to the shell by the ejector is a rearward movement and it is desirable that the shell be deflected to one side. For this purpose the top of the breech block is provided with a deflector surface 35 by which the shell is directed to one side, thus causing the shell to fall entirely clear of the firearm and the user thereof.

The embodiment of the invention illustrated in the drawing and described herein is to be understood as illustrative, rather than restrictive, the invention being susceptible to embodiment in other forms, all falling within the scope of the appended claims.

What is claimed is:

1. In a firearm, a receiver, a pivoted stud in said receiver, a breech block comprising an aperture adapted to receive said pivoted stud, co-operating breech locking shoulders on said breech block and receiver, the pivot stud receiving aperture in said breech block being elongated to insure engagement between said shoulders.
2. In a firearm comprising a pivoted breech block and an extractor device adapted for actuation by said breech block, an ejector mechanism comprising a plunger in engagement with said extractor and a spring impelled member adapted to engage and actuate said plunger.
3. In a firearm comprising a receiver, a breech block pivoted therein, an extractor device adapted for actuation by said breech block and a fore-end piece; an ejector device comprising a spring and spring follower housed in said fore-end piece and an ejector plunger associated with said spring follower and adapted to engage and actuate said extractor.

AUBREY L. LOWE.
